G. A. BRONDER,
VAPOR EXTRACTOR,
APPLICATION FILED APR. 9, 1919.

1,361,005.

Patented Dec. 7, 1920.

Inventor
Gaston A Bronder
By his Attorney
M. de Bommelle

UNITED STATES PATENT OFFICE.

GASTON A. BRONDER, OF BROOKLYN, NEW YORK, ASSIGNOR OF ONE-HALF TO
THOMAS COSTIGAN, OF NEW YORK, N. Y.

VAPOR-EXTRACTOR.

1,361,005.

Specification of Letters Patent. Patented Dec. 7, 1920.

Application filed April 9, 1919. Serial No. 288,872.

To all whom it may concern:

Be it known that I, GASTON A. BRONDER, a citizen of the United States, and resident of the borough of Brooklyn, in the county of Kings and State of New York, have invented certain new and useful Improvements in Vapor-Extractors, of which the following is a specification.

This invention relates to a vapor extractor, and with it a continuous current of heated air, vapors or gases are circulated around and about a charge of material, various minerals, shale and other substances, by means of which the gases and volatile ingredients of the charge of material operated upon are vaporized and forced to a sealed main discharge conduit. It is particularly characterized by means wherewith current of heated air and vapors or gases derived from the charge of material operated upon are forced through and about all portions of the charge of material without complicated mechanism. Extractors have been made by heating a charging chamber on the outside walls thereof and which have not thoroughly heated their charges in all portions, with consequent losses of valuable vapors and gases contained therein. With the present invention all portions of the charge are subjected to heated currents of air and gases and vapors and the consequent separation of remaining gases and vapors.

In the drawings, which represent an exemplification of the extractor. Figure 1 shows a partial section of Fig. 2 on the line 1, 1; Fig. 2 shows a top plan view of Fig. 1; Fig. 3 is a partial section of Fig. 2 on the line 3, 3 and Fig. 4 represents a partial section of Fig. 3 on the line 4, 4.

The extractor comprises a charging and heating chamber 20, preferably with the hopper bottom 21 and the roof 22. A discharge opening 23 with the door 24 is provided for the hopper bottom 21. An inlet opening 25 with the door 26 is provided for the roof 22. An air and vapor circulating outlet is indicated at 27. Inclined grates 28, having the central discharge opening 29, are located in the hopper bottom of the chamber 20. Inclined perforated triangular plates 30 fill the spaces between the grates 28. A movable grate section 32 is provided for the central discharge opening 29. The grate section 32 has the side arms 33 which terminate in the perforated bosses 34.

Hinge pins 35 extend from the inner face of the chamber 20 and support the bosses 34.

A rack 36 is formed in the lower face of the grate section 32. A grate operating shaft 37 is journaled in the bearings 38 and 39 of the hopper bottom 21, and has secured thereto the spur gear 40 which meshes with the rack 36, and the hand operating wheel 41.

A trap is connected to the roof 22 and comprises the U-shaped connection having 44 and 45 and the cover 46. The leg 44 is connected to the roof 22 over a gas and vapor outlet opening 47. The leg 45 extends through the cap 48 of the sealed discharge conduit or main 49.

A heater comprises the barrel 50 with the top head 51 and the bottom head 52. Heating tubes 53 in said heater extend through the heads thereof. A hood 54 with the chimney 55 is located upon the head 51. A pan 56 is secured to the head 52 and contains a gas burner 57 having the gas outlet pipes 58. At the lower end of the barrel 50 a conduit 60 connects the interior of the barrel 50 with the interior of the hopper bottom 21 below the grates 28.

A blower 61 is located above the cover 22 and has its inlet end connected with the outlet 27 only and its discharge end is connected to the barrel 50 over an opening 62 in said barrel. A motor 63 is connected to the blower 61.

To operate the extractor the chamber 20 is charged with the material to be treated through the inlet opening 25, after the door 24 of the discharge opening 23 has been tightly closed. Next the opening 25 is tightly closed by means of the door 26. The blower 61 is started and the gas burner 57 is lighted. Air is driven from the chamber 20 and forced down the barrel 50 on the outside of the heating tubes 53 and forced through the conduit 60 into the hopper bottom 21 below the grates 28.

The air is heated on its downward flow in the heater, by means of the heated air that rises on the inside of the heating tubes 53. The heated air on the outside of the tubes is forced through the charge in the chamber 20 and vaporizes the volatile portions thereof. Some of the gases and vapors produced again circulate through the heater 50, return to the chamber 20, rise in the leg 44, descend in the leg 45 and are discharged into the sealed discharge main 49 through 110

the water or other fluid contained in the latter. The gases and vapors may then be led to condensers not shown. After the charge has been sufficiently treated it is discharged 5 through the discharge opening 23, after the door 24 is swung to its open position, and after the grate section 32 is moved from under the opening 29, by means of the spur gear 40 and the hand operating wheel 41. 10 The process is then repeated with another charge. Some of the uncondensable gases produced may be collected in a holder, not shown, and used for the burner of the heater.

15 Having described my invention what I desire to secure by Letters Patent and claim is:

1. In an extractor the combination of a charging and heating chamber having a gas 20 and vapor outlet opening, a heater, a conduit connecting the interior of the chamber and heater, tubes extending through the heater, means to circulate heated air through the tubes, a sealed discharge main coacting with 25 the said gas and vapor outlet opening of the charging chamber and means to force air and generated vapor and gases through the heater on the outside of the tubes thereof and thence through said conduit, through 30 the charging chamber and through said gas and vapor outlet into the sealed discharge main, to extract the remaining gases and vapors from the charge of material operated upon.

35 2. In an extractor the combination of a charging and heating chamber having a gas and vapor outlet opening and inlet and discharge openings for a material to be treated, means to seal the latter openings, a heater 40 for the chamber, a conduit connecting the

interiors of the heater and chamber, tubes extending through the heater, a burner for the heater to circulate heated air through the tubes thereof, a blower with its outlet end connected with the interior of the heater, 45 and its inlet end connected with the interior of the charging and heating chamber, a U-shaped connection having a pair of legs, one of said legs connected to the gas and vapor outlet of the chamber and a sealed 50 main with the other leg extending therein.

3. In an extractor the combination of a charging and heating chamber having a gas and vapor outlet opening in the roof thereof and having a hopper bottom, said roof having an inlet opening and said hopper bottom having a discharge opening, doors for sealing both of the latter openings, a heater coacting with the chamber, heating tubes in the heater, a conduit connecting the 60 interior of the heater outside of the tubes with the interior of the hopper bottom of the chamber, a burner below the heater to produce streams of heated air through its tubes, a blower with its inlet end connected 65 to the charging and heating chamber and its outlet end connected with the interior of the heater at its upper portion and outside of its tubes, a sealed main coacting with the gas and vapor outlet opening in the roof 70 of the chamber, grates in the hopper bottom of the chamber having a central discharging opening, a movable grate section under the latter opening and means to move said grate section to discharge the contents of 75 the charging and heating chamber.

Signed at the borough of Manhattan in the county of New York and State of New York, this 24th day of March, A. D. 1919.

GASTON A. BRONDER.
